UNITED STATES PATENT OFFICE.

ROY EUGENE WING, OF DETROIT, MICHIGAN, ASSIGNEE TO BURROUGHS ADDING MACHINE COMPANY, OF DETROIT, MICHIGAN, A CORPORATION OF MICHIGAN.

ADDING-MACHINE.

1,118,938.

Specification of Letters Patent.

Patented Dec. 1, 1914.

Application filed March 31, 1913. Serial No. 753,631.

To all whom it may concern:

Be it known that I, Roy E. Wing, a citizen of the United States, residing at Detroit, in the county of Wayne and State of Michigan, have invented certain new and useful Improvements in Adding-Machines, of which the following is a specification.

The object of the present invention is to prevent the possibility of misoperation through excessive speed of reciprocation of the prime mover as for example the familiar crank-handle which is pulled forward and then released.

The invention relates more specially to that type of adding machines in which transfer or carrying operations occur at the close of an operation, which in the case of the crank-handle occurs just as that handle reaches the end of its return movement.

More specifically stated the object of the invention is to prevent misoperation due to commencing a new operation of the machine before there has been time for the transfer or carrying operation to be completed.

The invention has been developed more especially for use in the well-known Burroughs adding machine, a characteristic feature of which is the one-step movement of registering racks beyond normal at the close of an operation while engaged with the registering wheels whereby to effect the transfer or carrying of tens.

According to the particular form of embodiment of the invention hereinafter described the object in view is accomplished by putting the prime mover of the machine to some extent under the control of the registering racks so that a second initial stroke of the prime mover cannot be started until racks which have been conditioned for transfer or carrying movements complete such movements.

Referring to the accompanying drawings which form part of this specification and illustrate in detail the preferred form of embodiment of the invention, Figure 1 represents in right-side elevation a machine of the familiar Burroughs type having applied thereto an equipment for carrying out my invention, all parts being illustrated at normal; Fig. 2 is a horizontal section taken substantially on the line 2—2 of Fig. 1 and confined to an illustration of the special

equipment; Fig. 3 is a sectional elevation similar to Fig. 1 but illustrating a changed relationship of parts to show how the special equipment takes effect; Fig. 4 is a similar view illustrating a slightly different condition for the next step in the operation.

The machine proper is now so familiar through disclosures of numerous prior patents and through extensive commercial use, that it will be unnecessary to describe it or to make more than casual reference to parts thereof with which my special equipment co-operates. The prime mover may be taken as the handle shaft 300 or the counter shaft 100, according to whether the machine is hand-operated or power-operated. It is here shown as equipped for either hand or power operation. There is secured upon the shaft 300 the usual full-stroke sector 311 which co-operates with the familiar pawl 313 in hand operations of the machine. When power-driven it is now customary to disable this pawl, in which connection see Benner Patent 903,536, issued November 10, 1908, and Kilpatrick Patent 928,981, issued July 27, 1909. Whether or not the full-stroke pawl is operative, the sector is ordinarily free to start upon an initial stroke just at the time when any transfer or carrying operations would be in order. These operations are effected through the medium of springs and are not performed until the sector has just about reached the end of a return stroke and the pawl 313 has straightened to the position shown in Figs. 1, 3 and 4 or is free to do so, and hence there is a possibility of starting the sector on a new initial stroke before the transfer or carrying operations have been completed. This is of course equally true when the machine is power-operated and the pawl 313 is out of commission.

A brief reference to the transfer or carrying mechanism will be useful at this point. The reference numeral 610 designates the registering racks which have the usual slot-spring-pin connection with the registering levers 611 and the latter are as usual upheld normally as to their forward arms by a restoring frame or yoke 613. The reference numeral 413 designates the familiar transfer pawls which normally engage studs on the registering racks holding the

latter down in opposition to the springs which connect them to the levers 611. Normally the upper ends of the racks are spaced from a cross-rod 210^b which serves to limit their upward movements when released from the restraint normally imposed upon them by the pawls 413. In any operation of the machine the forward arms of the registering levers 611 move the length of the slots in the racks 610 and in the case of any racks which have been unlatched through depression of amount keys or otherwise, the associated levers 611 will in their further travel carry the racks down distances determined by the stops which the amount keys set or distances determined by backward rotation of registering wheels to zero, according to whether the operation is an itemizing one or a totaling one. The present invention is not concerned with the totaling operation so that may be dismissed from further consideration. The registering of an item is done upon the return or upward movement of displaced racks, and if any transfer pawl 413 is tripped in the course of this registering operation the associated rack 610 will be carried on up one step beyond its normal position, through the medium of the spring which connects it to the associated lever 611.

For the purposes of the present invention I specially form the racks for coöperation with a lock for the sector 311 so that any rack moving upwardly beyond normal will bring the lock into play to prevent the starting of a second initial stroke of the sector while the transfer or carrying movement of the rack is in progress. Thus, each rack is formed upon its rear edge with a cam projection or lug 610^a of limited vertical extent and inclined on top and underneath and formed with a very much abbreviated straight or flat end edge. These lugs are designed to coöperate with a cross-rod 10 which normally is just above them ready to be acted upon by the upper inclined side or edge of any one of the lugs as clearly illustrated in Fig. 1. This cross-rod forms part of a bail which comprises side bars 11 at opposite sides of the machine (Fig. 2) and radius links 12 hung from shafts or cross-rods 200 such as commonly employed under the keyboard of the machine. Obviously this provides a swinging structure which may be thrown rearwardly by the action of any one of the lugs 610^a upon the cross-rod 10. The right-hand side bar 11 of said swinging structure is in the neighborhood of the full-stroke sector 311 and coöperates with the lock which is to prevent the starting of an initial stroke thereof while any rack is moving upward beyond normal position. This lock takes the form of an arm 13 pivoted to a convenient frame plate of the machine and formed or provided with

a head 13^a which projects laterally for engagement with a shoulder 311^a of the sector 311. The forward side of this lock head is inclined for coöperation with a roller 11^a which is mounted upon a stud carried by a depending branch 11^b of the right-hand side bar 11 of the aforesaid swinging structure.

A spring 15 which connects the arm 13 to a frame stud, tends to lift the arm and hold it above the path of movement of the sector 311. The arm is normally so held by said spring as illustrated in Fig. 1 and the roller 11^a is at the base of the inclined face of the head 13^a. The forward movement of the swinging structure which is produced by gravity and also by the camming action of the inclined face of the head 13^a upon the roller 11^a under actuation by the spring 15, is limited by the contact of an arm 12^a against one of the cross-rods or shafts 200, said arm being secured to the rearward one of such cross-shafts to which the rear radius links 12 are secured, this rearward one being a rock shaft.

It will be clear from the above described relationship of parts that when any one of the racks 610 rises beyond normal its lug 610^a will thrust the swinging structure rearward and cause the roller 11^a thereof to act with a camming effect upon the lock head 13^a forcing the same down in front of the shoulder 311^a and thereby preventing movement of the sector 311. Thus the object of the present invention is accomplished according to the particular embodiment there- of here illustrated.

It is of course necessary that the sector be unlocked when the racks reach the limit of movement upwardly beyond normal for they remain there until the machine is again operated. The abbreviated character of the end faces or edges of the lug 610^a and the limited vertical extent of the lugs are features which provide for the necessary unlocking. Referring to Fig. 3, it will be noted that the rack there shown is at an intermediate stage in its movement beyond normal and the end edge or face of its lug is in contact with the rod 10 so that the lock is taking effect to prevent movement of the sector 311. Referring to Fig. 4 which shows the rack at the limit of its movement beyond normal, it will be noted that the lug has passed upwardly beyond the rod 10 so that the swinging structure has been able to return at once to normal position freeing the sector 311.

In order to guard against any possibility of relocking the sector when the rack is pulled down from its abnormal position or to guard against strain upon parts through unnecessary contact, the swinging structure is especially constructed so that camming action of the lugs 610^a upon the rod 10 in downward movement of the racks will have

no effect to swing said structure rearward. To this end the rod 10 is not mounted directly in the side bars 11 of the structure but in supplemental side pieces or arms 17 which are pivoted to the bars 11 respectively and formed forward of the pivots with laterally projecting lugs 17^a extending under portions of the bar 11 which project beyond the said pivots. Springs 17^c normally hold the arm 17 up with their lugs 17^a in contact with the bars 11 so that the arms are aligned with the bars. Obviously there will be no change in this relation when the lugs 610^a act upon the rod 10 in upward movement of the racks. However, when any one of those lugs acts upon the said rod in downward movement of a rack the springs 17^c will yield so that the lug may pass the rod without moving the swinging structure rearward but merely rocking the supplemental bar.

The above description has more especial reference to hand operation of the machine. In the case of power operation, it would be preferable to lock the starting system so as to prevent turning on the power and thus avoid straining of the parts through the application of power to operate them when in locked condition.

The starting system here illustrated is substantially that shown in the aforesaid Benner Patent 903,536 and comprises a finger bar 318 extending along the right-hand side of the keyboard, and levers operated thereby including one designated 312 which is fastened to one of the keyboard rock shafts 200. To this same shaft there is also secured, for the purposes of my invention, a forwardly and downwardly extending finger 18, the terminal upper edge of which normally stands just in rear of and in substantial alignment with the under edge of a lug at the upper end of an upwardly extending branch 11^d of the right-hand side bar 11 of the swinging structure. The formation at the upper end of this branch including said lug is in the nature of a hook which upon rearward swinging of said structure is adapted to engage over the end of the arm 18 as shown in Fig. 3 thereby preventing depression of the bar 318 which must necessarily be accompanied by movement of the lever 312. Thus closing of the clutch to operatively connect the motor with the machine is prevented while any rack is rising from normal position to effect a transfer or carry, though, as in the case of lock 18, there is an immediate unlocking as the rack reaches the end of such movement.

I claim:

1. In a machine of the character described, the combination of registering wheels, actuators therefor, transfer mechanism, a prime mover, and a lock therefor automatically rendered effective during transfer actuation

of any wheel, with provisions for keeping the lock out of action when resetting the parts by subsequent operation of the prime mover.

2. In a machine of the character described, the combination of registering wheels, actuators therefor, carriers for the actuators, slot-pin-spring connected thereto, transfer pawls normally restraining the actuators, a prime mover, a lock for the latter, and means operated upon by the actuators, when relieved from restraint of pawls, to set said lock.

3. In a machine of the character described, the combination of registering wheels, actuators therefor, having cam projections, carriers for the actuators, slot-pin-spring connected thereto, transfer pawls normally restraining the actuators, a prime mover, a lock for the latter, and a swinging structure operated upon by the actuator cams to set said lock.

4. In a machine of the character described, the combination of registering wheels, actuators therefor, having cam projections, carriers for the actuators, slot-pin-spring connected thereto, transfer pawls normally restraining the actuators, a prime mover, a lock for the latter, a spring-held locking arm having a head to engage the prime mover and a cam face, and a swinging structure operated upon by the cam projection of the actuators and having a roller to act on the cam face of said head.

5. In a machine of the character described, the combination of registering wheels, actuators therefor, having cam projections, carriers for the actuators, slot-pin-spring connected thereto, transfer pawls normally restraining the actuators, a prime mover, a lock for the latter, and a swinging structure operated upon by the actuator cams to set said lock, and having a spring-held pass-by portion yielding to the cams upon return movement of actuators.

6. In a machine of the character described, the combination of registering wheels, actuators therefor, transfer mechanism, a prime mover, a power drive applied thereto, starting devices, and a lock for the latter automatically rendered effective during transfer actuation of any wheel, with provisions for keeping the lock out of action when resetting the parts by subsequent operation of the prime mover.

7. In a machine of the character described, the combination of registering wheels, actuators therefor, carriers for the actuators, slot-pin-spring connected thereto, transfer pawls normally restraining the actuators, a prime mover, a power drive applied thereto, starting device, a lock for the latter, and means operated upon by the actuators, when relieved from restraint of pawls, to set said lock.

3. In a machine of the character described, the combination of registering wheels, actuators therefor having cam projections, carriers for the actuators, slot-pin-spring connected thereto, transfer pawls normally restraining the actuators, a prime mover, a power drive applied thereto, starting de-

VICES, and a swinging structure operated upon by the actuator cams and adapted to engage and lock the starting devices.

ROY EUGENE WING.
